UNITED STATES PATENT OFFICE

FRANK J. BARNES, OF DETROIT, MICHIGAN

COAT AND TROUSERS PRESS

Application filed November 7, 1929. Serial No. 405,350.

This invention relates to garment presses, and particularly to presses of simplified, readily portable and collapsible form, such as may be compactly stored when not in use.

5 An object of the invention is to adapt a press of the described character to exercise the function also of a combined garment press and coat hanger.

Another object is to provide means on a 10 combined garment press and hanger for holding the breast portion of a coat in an expanded and unwrinkled form.

A further object is to employ a wire member for the last mentioned purpose and to 15 adapt such wire for quick detachable engagement with the coat-supporting portion of the press.

Still another object is to provide an improved and highly simplified clip for clamping together coacting plates of a garment 20 press.

These and various other objects the invention attains by the construction hereinafter described and illustrated in the accompanying 25 drawing, wherein:

Fig. 1 is a view in front elevation of the assembled press, showing a pair of trousers carried thereby.

Fig. 2 is a rear view of the same.

30 Fig. 3 is an elevational edge view of the press.

Fig. 4 is a top view of the same.

Fig. 5 is a perspective view of the disassembled pressing plates.

35 Fig. 6 is a fragmentary vertical section, taken upon the line 6—6 of Fig. 1 and showing a provision for detachably mounting upon the press a coat-expanding wire member.

40 Fig. 7 is a cross sectional view of the same, taken upon the line 7—7 of Fig. 6.

Fig. 8 is a perspective view of a wire clip employed to clamp together the plates forming the press.

45 Fig. 9 is a fragmentary vertical section

taken on the line 9—9 of Fig. 2, showing in full lines an initial inserted position of the hooked wire support for the invention, and showing in dash lines the final or use position of said support.

In these views, the reference characters 1, 2, 3 and 4 designate respectively four plates which primarily comprise the present invention and which are cut, stamped, or otherwise fashioned from any suitable material. The 55 preferred material for said plates is a light and slightly flexible wall board of a thickness approximating one eighth of an inch. Such board is commonly manufactured from wood pulp, sawdust, or like material, and is available at low cost.

The above described plates are preferably not permanently connecting in any manner, but are adapted to be quick-detachably assembled in cooperative relation, as will presently appear.

The plate 1 is so proportioned and fashioned as regards its width and the contour of its upper edge as to adapt it for use as a coat-hanger. Thus, said edge has its central portion semi-circularly rounded to a small radius and inclines similarly downwardly at each side of said central portion, as indicated at 5 and conform to the shoulders of the coat. Preferably, said plate has secured to its top portion by brads 7 or other suitable means, a plate 6 having its upper edge conforming to and flush with that of the plate 1 and corresponding in width to the latter. It is preferred to attach to the 70 plate 1 a hook 8 of wire or like material, functioning as a hanger, and in the illustrated embodiment of the invention said hook has an elongated wire shank 10 secured between the plate 6 and a relatively small auxiliary plate 75 9 bradded or otherwise attached at its lateral edges to the plate 6. The lower end of the shank 10 is formed with a small hook 11 for engaging the lower edge of the plate 9, and when desired, the hangers 8, 10, 11 may be 80 85 90 95

entirely removed from the plate 1 by sliding said hanger downwardly to clear the hook 11 from the plate 9 and then rotating said hanger to position the hook 11 against the plate 6 so that the hanger may be freely withdrawn.

It is preferred to equip the plate 1 with means for expanding the breast portion of a coat hung on said plate, and the preferred means for this purpose is a bowed length of wire 12 having downwardly bent extremities 13 snugly insertable in sockets 14 drilled in small plates 15 secured for that purpose to the plate 6, one at each end thereof. Said sockets are reinforced preferably by suitable metal inserts such as the staples 16 driven into the plates 15 in registration with the upper ends of said sockets.

In assembling the described press, the plate 1 is laid upon a table or the like with its front face uppermost, and the plate 3 is positioned to abut the relatively reduced end of said plate 1. The garment to be pressed is then stretched upon the two plates 1 and 3, and its creased edges are slightly dampened and smoothed with the hands to eliminate all wrinkles. The plates 2 and 4 are then superposed upon the garment in respective registration with the plates 1 and 3, and a plurality of spring wire clips 17 are engaged with the registering edges of the plates 1 and 2, and 3 and 4 to clamp them tightly upon the garment.

In order to firmly interconnect the upper and lower plates of the press so that the pressing effect will not be interrupted at the joint therebetween, it is preferred to permanently secure to the remote faces of the plates 1 and 2 a pair of extension plates 18 having the full width of said plates, and projecting a short distance below same. These plates produce an overlapping between the upper and lower members of the press and assure continuity in a vertical direction of pressure applied by the spring clips 17. Preferably, two of said clips are engaged with the plates 17, at opposite edges thereof, as clearly appears in the drawing.

Reinforcing strips 19 are preferably applied permanently to the remote faces of the lower edges of the plates 3 and 4.

It will be noted that the clips 17 are of very simple form consisting merely of short lengths of spring wire bent to form similar portions crossing each other at a point adjacent to their free ends. In applying said clips, their divergent ends are first positioned to straddle the edges of the press plates, the clips being turned at an approximate right angle to their initial position, as they are pushed into clamping positions.

In pressing trouser legs, all four plates of the press are employed as described, while for pressing coat sleeves the plates 3 and 4 alone suffice. In using the press as a hanger, the

trousers are clamped in position, as has been described, the top portion thereof depending from the upper edge of the plate 2, as best appears in Fig. 1. The coat is mounted upon the plate 1, and its breast portion is held expanded by the wire 12.

When the described press is not in use, its four primary plates may be superposed one on another and thus adapted to be very compactly stored. In performing a pressing operation with the described press, the same may, if desired, be laid flat on a table or the like, and weighted to apply requisite pressure to a garment, without utilizing the clips 17.

The extreme simplicity of the described press permits its manufacture with a minimum of expense and labor.

While it is apparent that the illustrated embodiment of my invention herein disclosed is well calculated to adequately fulfill the objects and advantages primarily stated, it is to be understood that the invention is susceptible to variation, modification and change within the spirit and scope of the subjoined claims.

What I claim is:

1. In a device of the character described, the combination with a plate having an upper edge conforming to the shoulders of a coat and having a pair of sockets adjacent to said edge, of a bowed wire member for expanding the breast portion of a coat, said element having down-turned ends removably inserted in said sockets.

2. In a device as set forth in claim 1, a pair of metallic elements secured to said plate and reinforcing said sockets.

3. In a device of the character described, the combination with a presser plate having a top edge substantially conforming to the shoulders of a coat, adapting said plate for coat hanger use, a second plate parallel and adjacent to the first mentioned plate, means securing the second plate along each lateral margin thereof to the first plate, and a supporting hook having a shank rotatively and slidably positioned between the two plates, its lower edge being hooked, whereby said shank may be slid downwardly between the two plates with its lower hook parallel to said plates, and may then be rotated through a quarter turn and upwardly shifted to engage its lower hook with the lower edge of the second plate.

4. A garment press comprising two pairs of plates each completely detachable from the others, the plates of each pair lying parallel and adjacent to each other, the plates of each pair abutting end-wise those of the other, means for clamping the plates of each pair in their parallel adjacent relation, and an extension rigidly secured to one plate of each pair, substantially coextensive in width with such plate and freely overlapping the abutting plate of the other pair, and additional

clamping elements each engaging both of said extensions.

5. In a device of the character described, the combination with a coat hanger having a front and rear face and having a pair of sockets opening in its front face and extending downwardly at a rearward inclination, of a breast expander having extremities removably fitting in said sockets, and forwardly bowed between said extremities.

10. 6. In the combination set forth in claim 5, means reenforcing each of the socket-forming extremities of the coat hanger.

15. In testimony whereof I sign this specification.

FRANK J. BARNES.
